BIAIS-LACE KNITTED NECKTIE

1,073,050.

Specification of Letters Patent. Patented Sept. 9, 1913.

Application filed March 24, 1913. Serial No. 753,650.

To all whom it may concern:

Be it known that we, JOSEF KELLNER, a subject of the Emperor of Germany, and SIDNEY Worms, a citizen of the United States, residing, respectively, at Brooklyn, in the county of Kings and State of New York, and New Rochelle, in the county of Westchester and State of New York, have invented certain new and useful Improvements in Bias-Lace Knitted Neckties, of which the following is a specification.

The present invention relates to neckties, and more particularly to knitted neckties, the object thereof being to provide a knitted necktie with a stripe of a peculiar form, as for instance as of lace formation knitted therein on a true or substantially true bias.

Another object of the invention is the provision of a knitted necktie having knitted therein stripes of different formation on a bias.

Another object of the invention is the provision of a bias knitted necktie having bias knitted stripes therein of different formations, and of different or contrasting color or colors to the body of the tie and to each other if preferred, and to provide such a necktie with a narrow neck portion merging into a flaring end or ends, the manner of knitting being shown and described in my contemporaneously pending application for the process, Serial No. 753,650, filed March 11, 1913, from which it will be observed that the tie is knitted upon a flat knitting machine having a pair of inclined needle beds and differential tension mechanism for giving proper tension to the work as it is knitted, the different forms of stripes being obtained by racking or jogging one of the needle beds relatively to the other in different ways.

The figure of the drawing is a plan view of this improved necktie, fragments of the knitting only being shown.

The knitted necktie 2 is so knitted that its thread loops 3 are located on a bias, which in the present instance is a true or substantially true bias, this being obtained by racking or jogging one, as the rear needle bed, so as to cause the thread loops or stitches of the needles thereof to be racked alternately first in one direction and then in the opposite; the true bias stripe 4 being obtained during this form of knitting by feeding or shooting into the tie at intervals if

a series is to be formed, a thread or threads of contrasting color or colors. The stripes may be of different widths and there may be as many stripes of this form as may be desired, as illustrated at 5 and 6. At a desired point in the tie, the bias stripe 7 is formed of a different form from the stripes 4, 5 or 6, in that it may have a lace effect or various other effects. This formation of stripe likewise located on a bias is obtained by racking or shogging one needle bed, as for instance the rear needle bed in a different manner from the racking hereinbefore referred to, as for instance by racking or shogging the needle bed step by step a plurality of times, first to one side, and then in a similar manner to the other side of the thread loops of the other needle bed.

In knitting this improved tie, the tie is started with a certain width in the machine, it being started for instance at its end 7', and by gradually throwing out of operation certain needles on one side, it will have a gradually narrowed or tapered effect when it is made up, this taper continuing until the neck-band 8 is reached, the edges of which will be knitted straight, and then to form the other flared end 9 certain needles on one side are gradually thrown into operation. The ends are subsequently shaped and over-edged.

At certain intervals in the tie, a different or contrasting colored thread is shot thereinto to form the diagonal stripes 4, when these are provided. During the knitting of the body of the tie and of these stripes 4 the needle bed is racked or shogged in one manner, as for instance alternately, in opposite directions. When the lace formed stripe 7 is to be formed then the racking or shogging of the needle bed is changed so that it will be racked or shogged a plurality of steps first in one direction and then in the opposite direction. Of course, it will be understood that this racking or shogging takes effect before the carriage carrying the cam locks engages the needles.

From the foregoing it will be observed that this improved tie is knitted flat with its lateral edges 10 subsequently connected as by sewing, as distinguished from a tubular knit tie, and furthermore the stripes 4, 5 and 6, have substantially the same appearance on both sides thereof, and while the stripes 7 when of a lace effect have a wrong

side and a right side, yet their appearance is very much the same on both sides, and the stitches or loops of all the stripes are not loose and flowing on the rear side of the fabric. The tie as hereinbefore stated has its thread loops running on a bias, so that it will unravel on a bias, and it apparently has longitudinally extending wales and horizontal thread courses.

- 10 The term lace as used herein and in the claims is intended to mean and cover a portion or stripe of a different form or structure from the stripe shown in applicants' allowed case, Serial No. 721,358, filed September 20, 1912, and it is therefore intended to mean and cover an open mesh or open work stripe which is different from a continuous solid form of stripe such as shown in applicants' companion case.
- 15 20 We claim as our invention:
1. As an article of manufacture, a bias knitted necktie having therein knitted on a bias, a lace formed stripe.
  2. As an article of manufacture, a flat 25 knitted necktie having knitted therein a lace

formed stripe located on a substantially true bias.

3. As an article of manufacture, a bias knitted necktie having knitted therein on a substantially true bias, a plurality of stripes, 30 one of a different structure from another.

4. As an article of manufacture, a necktie knitted flat, with its thread loops on a bias from end to end of the tie, and having a narrow neck portion merging into a gradually widened flaring portion or portions, each terminating in a shaped end or ends; said tie having its rear lateral edges suitably connected, and also having knitted therein a plurality of true bias stripes, one 35 or more of a contrasting color or colors, and one or more of open mesh work.

Signed at New York this 13th day of August, 1913.

JOSEF KELLNER.
SIDNEY WORMS.
